UNITED STATES PATENT OFFICE.

ERWIN E. DREESE, OF EUCLID VILLAGE, AND WILLIAM LAVIGNA, OF UNIVERSITY HEIGHTS, OHIO, ASSIGNORS TO THE LINCOLN ELECTRIC COMPANY, OF CLEVELAND, OHIO, A CORPORATION OF OHIO.

END BRACKET FOR DYNAMO-ELECTRIC MACHINES.

Application filed July 29, 1927. Serial No. 209,213.

In a co-pending application of William Lavigna, one of the applicants herein, filed June 23, 1927, Serial No. 200,842, a novel construction of end bracket for dynamo electric machines is disclosed and claimed, such construction being characterized by the substitution for the cast iron bracket, heretofore customarily employed in this connection, of a bracket fabricated out of structural steel shapes. Specifically such improved bracket comprises a central cylindrical steel portion that forms the bearing box for the shaft or spindle of the machine, a bracket ring of structural steel stock made from an elongated structural steel member formed into a circle and having its ends welded together, and buttress-legs welded to such box and bracket ring.

The present improvements relate more particularly to a fabricated end bracket of the type in question in which the bearing box is likewise assembled from structural steel members. Still more particularly the present improvements relate to an end bracket with a bearing box adapted to receive a so-called split bearing. Incidentally certain modifications in the structure of the end bracket itself are involved.

To the accomplishment of the foregoing and related ends, the invention, then, consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

In sad annexed drawing:—

Fig. 1 is a front elevation of our present improvement end bracket and bearing box, the front wall of the latter being removed in order better to show the interior construction of such box; Fig. 2 is a broken central section thereof taken on the vertical plane indicated by the line 2—2, Fig. 1; Fig. 3 is a rear elevation of the box by itself; Fig. 4 is a plan view of the lower portion of said box; Fig. 5 is a central vertical section of such lower portion, the plane of the section being indicated by the line 5—5, Fig. 4; Fig. 6 is a plan view of the upper portion of the box; Fig. 7 is a central vertical section there-

of taken on the plane indicated by the line 7—7, Fig. 6; Fig. 8 is an end view of such upper box portion; and Fig. 9 is a broken plan view of an assembly detail, the parts shown lying partly in the plane indicated by the line 9—9, Fig. 1.

The principal element or base of the end bracket is a ring made up of two parts 1 and 2, the former being somewhat less and the latter somewhat greater than a semi-circle in extent. In other words, the ring is cut in two on each side in the plane defined by the line 9—9, Fig. 1. This ring, as in the case of the continuous ring constituting the end bracket in the aforesaid co-pending application, is formed of structural steel stock, specifically from angle bar stock, suitable lengths hereof being cut and beveled at their ends so that upon bending the pieces into the approximately semi-circular form just described and then bringing the ends of the two pieces into abutment, a complete ring shaped piece is had. However, in the present construction the abutting ends are not welded together, but the upper section 1 of the ring is separable from the lower section 2, as will be presently set forth in detail. The resulting ring (see Figs. 2 and 9) presents the form of a centrally directed flange 3 and a peripheral cylindrical portion 4, the edge of the latter being rabbeted to fit a complementary rabbet on the stator end ring 5 that forms a part of the main frame of the machine.

The bearing box, which is located approximately centrally with respect to the aforesaid ring, comprises a main portion 6 and a supplemental portion 7, both of general rectangular shape and each being formed out of pieces of structural steel stock, i. e., angle bar or channel stock cut to the proper length. Thus, such portion 6 of the box, as best shown in Fig. 1, is formed of two similar pieces of angle bar stock 6^a, brought together with the edges of two flanges in abutting relation and the seam along such edges completed by welding, as for example by an arc pencil or a carbon arc into which a pencil of welding metal is introduced. The portion 7, which is not as deep as the main portion 6, may be similarly formed by welding two pieces of angle bar stock together, but is more conveniently made out

of a single piece of channel bar stock as shown. While such portion 7 is shallower than portion 6, it is of the same width and the edges of the channel bar section composing the former are brought into abutting relation with the adjacent edges of the lateral upstanding flanges of angle bar sections 6^a and the seam along such edges welded as before, so that the upper surfaces of the two component sections 6 and 7 will lie in the same plane. A plate 8 is welded to the front face of box portion 6, such plate having a semi-circular opening 8^a in its upper edge, and a second plate 9 to the rear portion thereof below box portion 7 so as to form a receptacle in the main portion of the box for oil or other lubricant.

A common closure 10 for the two portions 6 and 7 comprising the box is formed out of a section of channel bar stock, as shown in Fig. 1, the front end of the cover thus provided being closed by a plate 11 having a semi-circular opening 11^a therein complementary to that in plate 8. The lower edges of the depending flanges of cover member 10 of the box are preferably rabbeted so as to form a tight fitting joint where they rest on the upstanding flanges of the box portions 6 and 7.

30 In order to secure the bearing proper in the box, two similar transversely extending seating members 16 adapted to receive and support the lower half 12 of such bearing are welded at their respective ends to the side walls of portions 6 and 7 of the box, and the box cover 10 is similarly provided with centrally located seats 18 adapted to receive the upper half of such bearing. A cap screw 20 serves to clamp the two halves 40 of the bearing together, while a set screw 19 prevents the bearing from turning in the seat thus provided. Said box cover 10 is detachably secured to the box by means of set bolts 20 passing therethrough and having 45 threaded engagement in one of said members 16. The rear end of box portion 7 is provided with a plate 21, having a central opening that is grooved to receive an oil retaining ring, as will be readily understood.

50 The buttress-legs 22 are preferably spaced as shown, i. e., two are disposed in a transverse diametral plane, the other depending downwardly so as to give free access to the upper portion of the bearing box and more 55 particularly to permit the free removal of the box cover 10 with the upper half 17 of the bearing. It is in order, to give still more ready access to the bearing, that the upper portion 1 of the ring that forms the 60 base of the bracket structure is made in a separate piece from the lower portion 2 of such ring. In order to detachably secure the upper portion to the lower portion, inwardly directed angular lugs 23 are welded to the

front face of such ring portion 1 adjacent its respective ends and set bolts 24, passing through the horizontal portions of such lugs, serve fixedly to attach the same and thus the ring portion to the horizontal flanges 25 of the respective transversely disposed buttress-legs 22.

70 Other modes of applying the principle of our invention may be employed instead of the one explained, change being made as regards the mechanism herein disclosed, provided the means stated by any of the following claims or the equivalent of such 75 stated means be employed.

We therefore particularly point out and distinctly claim as our invention:—

80 1. In an end-bracket for a dynamo-electric or like machine, the combination of a ring member made from structural steel, a split bearing box, and buttress legs welded at their respective ends to said ring member and one section of said box, the sections of 85 the latter being made of pieces of structural steel.

90 2. In an end-bracket for a dynamo-electric or like machine, the combination of a segmental ring member made from structural steel, a split bearing box, and buttress legs welded at their respective ends to said ring member and the lower section of said box, 95 said section being made of pieces of structural steel welded together to form one portion of greater depth than the other.

100 3. In an end-bracket for a dynamo-electric or like machine, the combination of a segmental ring member made from structural steel, a split bearing box, and buttress legs welded at their respective ends to said ring member and the lower section of said box, 105 said section being made of pieces of structural steel welded together to form one portion of greater depth than the other, and the upper section of said box being detachable from such lower section and likewise made of a piece of structural steel.

110 4. In an end-bracket for a dynamo-electric or like machine, the combination of a segmental ring member made from structural steel, a split bearing box, and buttress legs welded at their respective ends to said ring member and one section of said box, the sections of 115 the latter being made of approximately rectangular pieces of angular steel stock and plates welded together.

120 5. In an end-bracket for a dynamo-electric or like machine, the combination of a segmental ring member made from structural steel, a split bearing box, and buttress legs welded at their respective ends to said ring member and one section of said box, the sections of 125 the latter being made of approximately rectangular pieces of steel channel stock and plates welded together.

6. In an end-bracket for a dynamo-electric

or like machine, the combination of a segmental ring member made from structural steel, a split bearing box, and buttress legs welded at their respective ends to said ring member and the lower section of said box, said section being made of two pieces of steel channel stock having flanges of different depths welded end to end with the edges of such flanges in alignment and plates welded 10 to the exposed ends of said pieces.

7. In an end-bracket for a dynamo-electric or like machine, the combination of a segmental ring member made from structural steel, a split bearing box, and buttress legs 15 welded at their respective ends to said ring member and the lower section of said box, said section being made of two pieces of steel channel stock having flanges of different depths welded end to end with the edges of 20 such flanges in alignment and plates welded to the exposed ends of said pieces and the upper section of said box being detachable from such lower section and made from a single piece of steel channel stock.

25 8. In an end-bracket for dynamo-electric and like machines, the combination of a ring comprising two segmental members

each made from a piece of structural steel and detachably secured together at their corresponding ends, a split bearing box, and 30 buttress legs welded at their respective ends to one of said ring members and one section of said box.

9. In an end-bracket for dynamo-electric and like machines, the combination of a ring 35 comprising two segmental members each made from a piece of steel angle bar stock properly circled with one flange of the bar constituting a cylindrical portion and the other a flat inwardly directed portion, a split 40 bearing box, and buttress legs welded at their respective ends to one of said ring members and one section of said box.

10. In an end-bracket for dynamo-electric or like machine, the combination of a ring 45 comprising two segmental members detachably secured together, a split bearing box, and buttress legs welded at their respective ends to one of said ring members and one section of said box. 50

Signed by us this 25th day of July, 1927.
